(57) **CLAIM**

The ornamental design for a protective gown as shown and described.

DESCRIPTION

FIG. 1 is a front perspective view showing our new design for a protective gown shown in a first configuration;

FIG. 2 is a front view thereof;

FIG. 3 is a rear view thereof;

FIG. 4 is a right side elevation view thereof;

FIG. 5 is a left side elevation view thereof;

FIG. 6 is a top view thereof;

FIG. 7 is a bottom view thereof;

FIG. 8 is a front perspective view thereof shown on a person;

FIG. 9 is a rear perspective view thereof; and,

FIG. 10 is a rear perspective view of the design shown in FIG. 1 shown in a second configuration.

The broken lines shown in the Figures show portions of the protective gown or environment that form no part of the claimed design.

The shade stippling in the Figures show contour and do not claim surface ornamentation or treatment.
